UNITED STATES PATENT OFFICE.

PERCIVAL DIGNAN, OF NEW YORK, N. Y.

RIBBON-SUPPORTING MECHANISM.

1,241,464.

Specification of Letters Patent. Patented Sept. 25, 1917.

Continuation in part of application Serial No. 61,004, filed November 12, 1915. This application filed May 13, 1916. Serial No. 97,378.

To all whom it may concern:

Be it known that I, PERCIVAL DIGNAN, a citizen of the Commonwealth of Australia, and a subject of the King of Great Britain, 5 and a resident of the borough of Manhattan, city, county, and State of New York, have invented certain new and useful Improvements in Ribbon-Supporting Mechanism, of which the following is a specification.

10 My invention relates to mechanism for supporting and moving an inking ribbon.

One object of my invention is to provide mechanism for supporting an inking ribbon and moving it to present a fresh portion to 15 be acted upon.

Another object is to provide inking-ribbon supporting and moving mechanism in which the moving mechanism is reversible.

Another object is to provide reversing 20 inking-ribbon moving mechanism, the reversing of which is controlled by the ribbon.

Other and further objects and advantages will appear from the following description, taken in connection with the drawings forming 25 part of this specification, and will be pointed out in the hereunto-annexed claims.

In the accompanying drawings, in which like reference characters indicate similar parts,

30 Figure 1 is a plan view of an inking-ribbon device embodying a preferred form of my invention.

Fig. 2 is a partial sectional view of the device shown in Fig. 1, with parts removed; 35 and

Fig. 3 is a sectional view of one of the ribbon reels, showing a part of the reversing mechanism.

My co-pending application, Serial No. 40 61,004, filed November 12, 1915, for printing machines, discloses an inking ribbon supporting and moving mechanism and the invention herein disclosed embodies the broad features of said mechanism and this specification constitutes a continuation so far as 45 any common subject-matter is concerned of the said co-pending application.

In order to disclose my invention, a preferred embodiment thereof is herein described and illustrated, but it is to be understood that my invention contemplates all variations, modifications and adaptations which may occur to those skilled in the art, and it is to be understood that my invention

is not limited to the specific details herein 55 set forth for the purpose of disclosing it.

Ribbon-supporting mechanisms embodying my invention may be used in connection with a great number of devices, among which may be mentioned printing devices, 60 and it is evident that there will be a base plate of some character, such, for instance, as the base plate 1, upon which the mechanism is mounted. Plates 2 and 3' support the ribbon reels 3 and 4, respectively, upon 65 shafts 5 and 6. Between the end of each reel and the plate 2, there is positioned a thrust washer 7, and a spring 8, encircling the shaft of each reel, is held under tension by the lock nuts 9, so that the reels are held 70 against moving too freely. A reel-turning member 10, comprising in this embodiment of my invention a flat plate, is mounted for reciprocation. In this embodiment, the mounting of the reel-turning member is ac- 75 complished by passing screws 11 through slots 12 in the plate 10 and into the plate 3'. Fixed, respectively, to the shafts 5 and 6 are ratchet wheels 13 and 14, and pawls 15 and 16, mounted upon the reel-turning member 80 10, respectively coöperate with the ratchet wheels 13 and 14. The pawls are pressed toward their corresponding ratchet wheels by the springs 17, and are restrained from coöperating with the ratchet wheels when co- 85 operation is not desired by the pins 18, as will be more fully described hereinafter.

Mounted upon the plate 3' are spring casings 19, in which there are mounted for reciprocation cam members 20, which are 90 forced into their outermost position by springs 21, and the outermost position of which is limited by the lock nuts 22. Each cam member 20 has two active faces 23 and 24, positioned substantially at right angles. 95 The reel-moving member 10 has coöperating cams, comprising corresponding faces 23' and 24'. The mounting of the cam members 20 is such that the faces 23 coöperate with the faces 24', as shown in Fig. 3, or the 100 member 10 may be moved to the right so far that the edge or crest formed by the junction of the faces of the two cams 20 will slip past the edge or crest formed by the faces of the cams on the member 10 and the 105 faces 24 will coöperate with the faces 23'.

It will be seen that when the parts are in the position shown in Fig. 2, if the member

10 is moved to the right far enough to cause the pawl 16 to move the ratchet wheel 14 through a distance equal to the length of one tooth, but not far enough for the pawl 15 to engage a tooth of the wheel 13, and the member 10 is released, the tension of the springs 21 will force the cam members 20 down against the faces 24' on the member 10 and force the member 10 to the left, restoring it to one of its normal positions, so that the pawl 16 will engage the next tooth on the wheel 14, which may be called the active wheel, for the member 10 is so adjusted that wheel 14 has its corresponding pawl in operative relation thereto. It will be seen that reciprocation of the member 10 to this extent will cause a counter-clockwise rotation of the reel 4, so that the ribbon 25 will be wound upon it.

20 The ends of the reel-turning member 10 are beveled off at 26, and the sloping faces 27' of the actuating members 27 coöperate with the beveled faces 26. The members 27 are mounted upon the base plate 1 for sliding by means of the pins 28 passing through the slots 29, and also by means of the extensions 27" passing through the loops 30, which are secured to the base plate 1. Springs 32 surround the extensions 27" and 25 abut against the members 27 and the loops 30, and tend always to press forward the members 27. Links 33 are pivoted to the loops 30 and have connected to them, by means of a pin-and-slot connection 34, the 30 yoke 35, comprising separate arms, which are pivoted to and reciprocated by the link 36 by some mechanism, which may, for example, be a part of a printing machine of some character. Links 33' connect links 33 and member 27.

40 The members 27 are positioned relatively to the ends of the member 10, so that when the limiting members 37, which will be more fully described hereinafter, are in the position shown in Fig. 1, the pressure of the cams 20 upon the cam faces on the member 10 will position the member 10, so that the face 27' of only one member 27 will actively coöperate with a face 26, whereby a reciprocation of that member 27 will cause a reciprocation of the member 10. The limiting members will limit the movement of both the active and inactive members 27 under the action of its spring 32, so that the 50 member 10 will only be reciprocated far enough by the active member 27 to move the active ratchet wheel 14 a distance equal to one of its teeth. When the member 37, which is acting to limit the extent of movement of the active member 27, is moved out of the path of said member 27, the member 10 is moved by the said active member 27 far enough to cause the cams 20 to snap across the crest or edge of the faces 23' and 60 24', so that they coöperate no longer with

the faces 24' but do coöperate with the faces 23', and the pawl 15 is caused to engage the wheel 13, which thereafter becomes the active wheel.

It will be seen that, when the pawl 15 becomes the active pawl, a reciprocation of the member 10 will cause the ribbon to be wound upon the reel 3 instead of upon the reel 4. This constitutes a reversal of the ribbon-moving mechanism. In order to bring about this reversal, the proper limiting member 37 is withdrawn from the path of the active member 27, so that the member 27 may move forward under the action of its spring 32 far enough to give a greater reciprocation to the member 10 than is necessary to move the ratchet wheel through the distance equal to the length of one of its teeth, which will result in the snapping over of the cam members 20 from one set of faces, for example 24', to the other set of faces, for example 23', on the member 10.

It is perfectly apparent at this stage of the description that, when the cam members 20 are coöperating with the faces 24', the pawl 16 and the ratchet wheel 14 are active and the member 27 at the left of Fig. 1 is active. If the cam members 20 snap across to the faces 23', then the pawl 15 and the ratchet wheel 13 become active and the member 27 at the right of Fig. 1 becomes active.

The limiting members 37 are mounted on the opposite side of the plate 3' from that on which the member 10 is mounted. The limiting members 37 are mounted on the plate 3' by pins 38, passing through slots 39, and the limiting members are held in their outermost position, shown in Fig. 1, by springs 40. The cores 41 of the reels are provided with slots 42, which are divided by partitions 43. One end flange 44 of each reel has a sector 45 cut from it, and this sector is secured to plate 46, which fills up one end of the slot 42 and comprises a sector of the core 41, and which has attached to it one or more pins 47, which are surrounded by springs. These springs are under tension and act to slide the sectors 45 out of the slots in the end flanges 44 into which they fit, so that, as the ribbon 25 is unrolled from over the plate 46, the springs 47 will push out the sectors 45, so that they will strike against lugs 48 on the limiting members 37 and push the limiting members back out of the path of the members 27.

It will be seen from this structure that when the ribbon is so far unwound from one reel that the plate 46 of that reel is uncovered, the segment 45 will slide out, and, as the reel turns, it will strike against the lug 48 and push the limiting member 37 out of the path of the actuating member 27, so that the actuating member 27 may, under the action of the spring 32, move a greater distance than it ordinarily moves to rotate

the ratchet wheel through the distance of one tooth, and the member 10 will be moved so far that the cam members 20 will snap across from one set of cam faces on the member 10 to the other set of cam faces on the member 10, and the other actuating member 27 will thereupon become active and impart short reciprocations to the member 10, thereby causing the ribbon to wind upon the 10 other reel until there is a reversal of the mechanism similar to that above described.

The connection between the links 33 and the yoke 35 is a pin-and-slot connection, so that the movement of the link 36 and the 15 yoke 35 may be always of the same magnitude, regardless of what limitation may or may not be placed upon the movement of the members 27.

It is particularly to be noted that I do not 20 intend that my invention shall be limited to the particular means for securing the reciprocation of the members 27, and to the particular means, namely the spring-pressed cams 20, for securing reciprocation of the 25 reel-moving member 10, nor do I intend that my invention shall be limited to the specific means which I have shown for bringing about a reversal of the ribbon-moving mechanism.

30 What I claim as new and desire to secure by Letters Patent of the United States is the following:—

1. In a ribbon-supporting mechanism, a plurality of ribbon reels, a reel-rotating member adjustable to coöperate with either of said reels, means for imparting motion thereto to effect the adjustment thereof and to effect the rotation of said reels, the result effected being dependent upon the extent of 40 action of said means, and means for controlling the extent of such action, dependent upon the condition of the ribbon.

2. In a ribbon-supporting mechanism, ribbon reels, a reel-rotating member, said member being reciprocable at a plurality of positions respectively corresponding to and for coöperation with said reels, and a single member coöoperating with said first-named member for reciprocating said first-named 50 member and positioning it.

3. In a ribbon-supporting mechanism, ribbon reels, a reel-rotating member, said member being reciprocable at a plurality of positions respectively corresponding to and for 55 coöperation with said reels, and a single member coöoperating with said first-named member for reciprocating said first-named member and setting it, the positioning action of said means being dependent upon the 60 condition of the ribbon.

4. In a ribbon-supporting mechanism, a ribbon reel, means for rotating said reel, including a reciprocating member, means for actuating said reciprocating member in one 65 direction, a stationary member, a cam

formed on one of said members, and a yieldably-supported cam mounted on the other of said members and coöperating with said first-named cam to restore said member.

5. In a ribbon-supporting mechanism, a 70 ribbon reel, means for rotating said reel, including a reciprocating member, means for actuating said reciprocating member in one direction, a stationary member, a two-faced cam formed on one of said members, 75 and a yieldably-supported cam mounted on said other member and coöperating with said first-named cam to restore said reciprocating member or carry it from coöperative relation with said reel according to the face 80 of said two-faced cam acted upon by said other cam.

6. In a ribbon-supporting mechanism, a ribbon reel, means for rotating said reel, including a reciprocating member, means 85 for actuating said reciprocating member in one direction, a stationary member, a two-faced cam formed on one of said members, a yieldably-supported cam mounted on said other member and coöperating with said first-named cam to restore said reciprocating member or carry it from coöperative relation with said reel according to the face of 90 said two-faced cam acted upon by said other cam, and means controlled by the condition 95 of the ribbon for causing a change of co-operation of said cams from one face to the other.

7. In a ribbon-supporting mechanism, a plurality of ribbon reels, a reel-rotating 100 member adapted to be adjusted to rotate either of said reels, a stationary member, a two-faced cam mounted on one of said members, a yielding cam mounted on the other said member and coöperating with either 105 face of said first-named cam according to the adjustment of said rotating member, said cams constituting restoring means for said rotating member, and actuating means for said reel-rotating member. 110

8. In a ribbon-supporting mechanism, a plurality of ribbon reels, a reel-rotating member adapted to be adjusted to rotate either of said reels, a stationary member, a two-faced cam mounted on one of said 115 members, a yielding cam mounted on the other said member and coöperating with either face of said first-named cam according to the adjustment of said rotating member, said cams constituting restoring means 120 for said rotating member, actuating means for said reel-rotating member, and means controlled by the condition of the ribbon for changing the adjustment of said rotating member. 125

9. In a ribbon-supporting mechanism, a plurality of ribbon reels, reversible rotating mechanism therefor, mechanism for actuating and reversing said first-named mechanism according to its extent of operation, 130

and ribbon-controlled means for controlling the extent of operation of said last-named mechanism.

10. In a ribbon-supporting mechanism, a plurality of ribbon reels, reversible rotating mechanism therefor, mechanism for actuating and reversing said first-named mechanism according to its extent of operation, means for limiting the extent of operation 10 of said last-named mechanism, and ribbon-controlled means for rendering inoperative said last-named means.

11. In a device of the class described, inking ribbon supporting means comprising 15 reels mounted for rotation for carrying said ribbon, a reel-rotating member mounted for reciprocation and arranged to coöperate with one reel at a time, a member having faces diverging from an apex and mounted 20 on said reel-rotating member, a spring-pressed member adapted to contact with either face of said last-named member, means for reciprocating said reel rotating member, a member normally operating to 25 limit the action of said last-named means, whereby said spring-pressed member is permitted to remain in contact with one of said faces, and means dependent upon the amount of ribbon on a reel for rendering 30 said limiting member inoperative, whereby said reel rotating member is moved to a position wherein said spring-pressed member coöperates with said other face and said ribbon-moving mechanism is reversed.

35. 12. In a device of the class described, inking ribbon supporting and moving mechanism comprising reels for winding up and unwinding the ribbon, reel-turning mechanism, said mechanism being adjustable to 40 coöperate with either reel, means to actuate said reel-turning mechanism, and means capable of being rendered inoperative for limiting the operation of said actuating means, said actuating means acting to 45 change the adjustment of said mechanism upon said limiting means being rendered inoperative.

13. In a ribbon-supporting mechanism, a plurality of ribbon reels, reversible rotating 50 mechanism for said reels, mechanism for actuating and reversing said first-named mechanism including a movable cam, a member for limiting the movement of said cam but permitting it to actuate said first-named mechanism to rotate said reels, and ribbon-controlled means for rendering inoperative said limiting member to permit 55 said cam to reverse said first-named mechanism.

60. 14. In a ribbon supporting mechanism, ribbon reels having ratchet wheels in driving relation thereto, a pawl carrying member reciprocable to positions to coöperate with said wheels one at a time and reciprocable at said positions to rotate said wheels,

all said reciprocations being substantially along the same line of movement, and means dependent upon the condition of the ribbon for controlling the reciprocation of said member.

15. In a ribbon supporting mechanism, ribbon reels, a reel-rotating means having a plurality of settings respectively for coöperation with said reels, means for actuating said rotating means and for effecting the 75 setting thereof according to the extent of operation of said actuating means, and means dependent upon the condition of the ribbon for controlling said actuating and setting means, whereby it acts to actuate 80 said rotating means and to set it according to the condition of the ribbon.

16. In a ribbon supporting mechanism, ribbon reels, means movable to rotate any one of said reels and movable to coöperate 85 with different ones of said reels to rotate them, means moving to impart motion to said first named means and means controlling the motion of one of said means whereby said first named means is moved to rotate a reel or is moved to coöperate with another one of said reels.

17. In a ribbon supporting mechanism, ribbon reels, means movable to rotate any one of said reels and from coöperation with 95 one to coöperation with another of said reels, according to the extent of motion thereof, and means dependent on the condition of the ribbon to limit the movement of said first named means.

18. In a ribbon supporting mechanism, ribbon reels, means movable to rotate any one of said reels and movable from coöperation with one to coöperation with another of said reels, and a single member to effect 105 the movement of said first named means to cause it to rotate one of said reels or to move it from coöperation with one to coöperation with another of said reels according to the condition of the ribbon.

19. In a ribbon supporting mechanism, a plurality of ribbon reels, means for rotating said reels and adjustable for coöperation with different reels, yieldable means for actuating said last named means to 115 cause it to rotate said reels or to move it to different adjustments according to the extent of operation of said second mentioned means, and means dependent upon the condition of the ribbon for obstructing the operation of said last mentioned means.

20. In a ribbon supporting mechanism, a plurality of ribbon reels, actuating members respectively for each reel, means constantly operating said members, and means 125 for transmitting motion to said reels from said members and adjustable for coöperation with different ones of said members, according to the condition of the ribbon.

21. In a ribbon supporting mechanism, a 130

plurality of ribbon reels, actuating members respectively for each reel, yieldable means for operating said members, means for transmitting motion to said reels from said members, according to the setting thereof, 5 said members acting to change the setting of said last mentioned means according to the extent of motion of said members, and means dependent upon the condition of the 10 ribbon for limiting the extent of motion of said members.

22. In a ribbon supporting mechanism, 15 ribbon supporting reels, a member reciprocable at positions corresponding to said reels to rotate said reels, means for reciprocating said member in one direction at each of said positions and a single means for reciprocating said member in another direction at each of said positions and for shifting 20 said member from one position to another according to the condition of the ribbon.

23. In a ribbon-supporting mechanism, a

plurality of ribbon reels, a reel-rotating member adjustable to coöperate with each 25 of said reels, means for effecting the adjustment of said member and for imparting motion thereto to effect the rotation of said reels, the result effected being dependent upon the extent of action of said means and 30 means for controlling the extent of such action dependent upon the condition of the ribbon.

24. In a ribbon-supporting mechanism, a 35 plurality of ribbon reels, a reel-rotating member adjustable to coöperate with either of said reels, means having a certain extent of movement to impart motion to said member to move said reels and a different extent of movement to effect the adjustment thereof 40 and means dependent upon the condition of the ribbon for controlling the movement of said last-named means.

In testimony whereof, I have signed my name to this specification.

PERCIVAL DIGNAN.
